VELVET OR TAPESTRY WEAVING

Frank W. E. Hoeselbarth, Carlisle, Pa., assignor to C. H. Masland & Sons, Carlisle, Pa., a corporation of Pennsylvania

Application June 12, 1950, Serial No. 167,534

16 Claims. (Cl. 139—39)

The present invention relates to patterned pile carpet produced on a velvet or tapestry loom.

This application has been divided and the fabric subject matter originally contained herein is now contained in U. S. application 255,991, filed November 13, 1951 for Velvet or Tapestry Carpet.

A purpose of the invention is to make patterned pile carpet on a velvet loom using a plurality of pile warps, stuffer warps, binder warps and wefts, without employing a jacquard or other selective pattern device.

A further purpose is to weave a plurality of different kinds of velvet carpet in admixture to produce various pattern effects in the same fabric, for example cut and uncut, wavy and straight, high and low, plain twist and frieze.

A further purpose is to obtain a clean even back of a patterned velvet carpet without any evidence of the pile yarn on the back.

A further purpose is to lower the cost of producing patterned pile carpet by keeping all of the pile at the face of the fabric, avoiding excess pile in or carried through the back as in jacquard weaves such as Wilton, and in W weaves and according to U. S. Patent No. 2,073,227.

A further purpose is to accelerate the process of weaving patterned pile carpet.

A further purpose is to raise a plurality of velvet carpet pile warps over different types of wires such as cutting and non-cutting, wavy and straight, high and low, and wide and narrow.

A further purpose is to employ different characters of yarn in respect to materials, construction or color in different velvet carpet pile warps.

A further purpose is to obtain stiffer fabric by employing several stuffer warp ends at a single dent or longitudinal line in a patterned velvet weave.

A further purpose is to obtain a plurality of pile warps from a single beam.

A further purpose is to obtain desirable pattern or similar effects in a velvet carpet weave by employing unequal distribution of pile warp ends in a pile warp and desirably in a plurality of pile warps, for example, leaving ends-out at certain dents, employing a plurality of pile warp ends at certain dents and employing different numbers of pile warp ends at different dents.

A further purpose is to utilize a cooperative pattern thread-in arrangement between two or more pile warps in a velvet carpet weave, for example leaving ends-out at a particular dent in both pile warps, employing a plurality of ends at a particular dent in both pile warps, leaving ends-out at a particular dent in one pile warp and employing an end-in or a plurality of ends-in at the corresponding dent of the other pile warp, and inter-relating the situation regarding ends-in and ends-out in adjoining dents of each or all of the pile warps in accordance with a pattern which will produce a desirable effect on the pile.

A further purpose is to distribute the stuffer warp in

2

a velvet weave from a raised position above the top of the shed, suitably over a guide or raised jumbo.

5 A further purpose is to manipulate pile warps by pile warp heddles and to manipulate the stuffer warp by the same heddles, desirably employing long slots in the pile warp heddles to manipulate the stuffer warps.

A further purpose is to make eyes and long slots below the eyes in the pile warp heddles.

10 Further purposes appear in the specification and in the claims.

In the drawings I have chosen to illustrate a few only of the numerous embodiments in which my invention may appear, selecting the forms shown from the standpoints of convenience in illustration, satisfactory operation and clear demonstration of the principles involved.

15 Figures 1 to 4 inclusive are weave diagrams of a complete loom cycle, each view showing a different pick in the preferred weave of the invention, the warps extending in the plane of the paper.

20 Figure 3a is a diagrammatic enlargement of the newly formed fabric of Figure 3, at the extreme right end of Figure 3.

Figure 4a is a diagrammatic enlargement of the newly formed fabric of Figure 4, at the extreme right end of Figure 4.

25 Figure 5 is a diagram corresponding to Figure 1 and showing a variation.

Figure 6 is a loom thread-in diagram of the weave of Figures 1 to 5 inclusive, illustrating only the warps and heddles.

30 Figure 7 is a modified loom thread-in diagram similar to Figure 6.

Figures 8 to 12 inclusive are fragmentary perspectives of repeats of various wire sets used in producing the 35 weaves of Figures 8a to 12a inclusive, each wire set being placed beside the corresponding weave to indicate the relationship. It will be understood that the complete wire set of the loom is a repetition of the wire set repeat shown in Figures 8 to 12, up to the total number 40 of wires used.

Figures 8a to 12a are conventional weave diagrams with the warps in the plane of the paper, and transverse to the wires and wefts, showing various weaves prior to withdrawal of the wires.

45 Figures 13 to 15 inclusive, are thread-in diagrams illustrating in each case at the left the thread-in pattern at the particular dent under consideration, and showing diagrammatically at the right the effect of that thread-in pattern on the pile projections at or adjoining that 50 dent.

Figure 16 is a thread-in chart showing in vertical columns the situation in eight different dents, showing in the top horizontal column the conventional thread-in diagram for each dent, and suggesting in the lower horizontal columns the conditions created in the respective warps at different weft positions in the various dents. In the relationship between one pile projection and another, Figure 16 may be regarded as a plan view, but in the showing of the pile projections it is purely diagrammatic.

60 Figure 17 is a thread-in diagram showing in horizontal rows 10 different thread-in patterns, and showing in vertical columns the thread-in repeats of various adjoining dents.

65 Figures 18, 19 and 20 are top plan views of portions of a "blanket" woven with thread-in patterns numbers 1 to 8 of Figure 17, using various wire sets as described in the specification. These views show the face of the carpet in accordance with one aspect of the invention.

70 Figure 21 is a bottom plan view of the blanket of Figures 18 to 20 inclusive.

Figures 22, 23 and 24 are thread-in diagrams illustrating

at the left the thread-in pattern and at the right the conditions produced at a particular dent, viewed in weave diagrams in which the warps are in the plane of the paper.

Figures 24a, 24b, 24c and 24d are diagrammatic top plan views of pile carpets, useful in explaining the invention. Figures 24a and 24d are illustrations of the prior art.

Figures 25, 26 and 27 are fragmentary perspective views of a velvet loom which has been modified in accordance with the present invention.

Figure 28 is a fragmentary elevation of a pile heddle wire of the character employed in the loom of Figures 25 to 27 and in the weave of Figures 1 to 4 inclusive.

Figure 29 is an elevation, largely diagrammatic, of a heddle harness which may be employed in the modified loom of the invention, illustrating one of the modified heddle cams.

Figure 30 is a diagram showing the active faces of all of the heddle cams in front elevation.

In the drawings like numerals refer to like parts throughout.

In the prior art where it is desired to obtain a pattern without printing or without dyeing certain different lengths of the same yarn different colors, it is usual to employ a jacquard or other selective pattern mechanism. This is expensive not only because of the equipment required, but particularly because comparatively expensive pile yarn must be carried in the back of the fabric at points where it is not called for by the pattern, thus greatly increasing the consumption of face yarn. Also the jacquard mechanism is comparatively complicated compared to the simple harness cams employed in the present invention. Furthermore, the practical speed in jacquard weaving is only about half the speed which can be attained in the present process. Many of the prior weaves also involve the objectionable feature of producing a comparatively unattractive back of the fabric, since the pile yarn carried in the back is likely to show through the back and by virtue of its presence creates some non-uniformity in the back of the fabric.

In accordance with the present invention, it is possible to obtain attractive pattern effects on a velvet loom without resorting to printing, or to supplement the effects obtained by printing, with greatly reduced expense over usual selective pattern weaves. At the same time a uniform attractive back of the fabric is secured.

When reference is made herein to velvet carpet, it is intended to include tapestry carpet.

In accordance with the present invention, a pattern pile carpet is obtained on the velvet loom using a plurality of pile warps, with a stuffer warp, binder warps and wefts, without employing a jacquard. The weave may desirably produce a plurality of different kinds of velvet carpet in admixture to secure various pattern effects in the same fabric. For example the pile at various points may be cut or uncut, wavy or straight, high or low, plain twist or frieze, it may have one or a variety of different colors, and it may have a selective tendency to crowd or yield in a particular direction to contribute to the pattern effect.

The back of the fabric is entirely smooth, even and clean, since the face yarn is kept entirely at the face and does not travel through the back as in other usual carpet weaves, and does not pass under the back wefts as in the weaves according to U. S. Patent No. 2,073,227. This greatly decreases the cost of producing the fabric of the invention, there being no waste of face yarn in the fabric construction, such as is present in the reverse bends of the W weave, or by carrying the face yarn under the stuffer warp as in the familiar selective pattern weaves.

A wide variety of different wires can be employed as later explained. For example, some wires can be straight and others can be wavy, some wires can be high and others can be low, some wires can be wide and others can be narrow, and some wires can be cutting and others non-cutting. Any combination of different characters of pile

yarn can be used, varying in twist (plain twist or frieze), ply, composition (wool, rayon, etc.) and color.

The invention is not limited to employment of two different pile warps, any desired number of pile warps being employed, and two pile warps merely being illustrative of the fact that several can be employed. While these pile warps will usually be taken from different beams, where the take-up is equal and especially where the thread-in procedure permits, both pile warps can be taken from the same beam, separated by whip rolls before weaving. When reference is made herein to a whip roll, it is intended to include such mechanism, whether or not it may be designated as a jumbo because of its use on a particular warp.

The fact that the face yarn does not pass under the stuffer warps makes additional room available without thickening the back of the fabric and this can to advantage be used to stiffen the fabric by employing additional stuffer warp ends at each dent.

A wide variety of different thread-in procedures can be employed to give pattern effects. This aspect of the invention can be employed to advantage even where only one pile warp is being used.

The thread-in may vary in different dents, in the number of pile ends per dent, in the employment of ends-out or blank dents, in the cooperative relationship between an end-in or a plurality of ends-in or an end-out in one pile warp with the end-in or plurality of ends-in or end-out in the corresponding dent of the other pile warp or warps, and in the relation of the concentration of pile in each dent with the concentration of pile in adjoining dents and series of dents. Thus, as explained herein, patterns can be designed for a thread-in pile which will give distinctive effects on the appearance of the fabric wholly independently of such factors as the character of the wire and the character of the yarn.

It will be understood, of course, that combinations of differences in the character of the yarn of the various pile warps, differences in the character of the wires and differences in the thread-in can be employed to produce pattern effects which could not be accomplished by differences in one or two of these factors alone.

It is very desirable to accomplish the weave of the invention without increasing the number of heddles normally used on a velvet loom, and this can be done, as explained below, by utilizing the pile warp heddles cooperatively to function as a stuffer warp heddle, distributing the stuffer warp in a downward direction toward the shed, as from a raised guide roll. It will be understood that the guide roll can also function as a whip roll (or jumbo) in which case the use of another whip roll will be unnecessary. The heddle wires of the pile warp heddles are desirably equipped with eyes for the pile warps and also long slots below the eyes for the stuffer warp. It will be evident as later explained that the stuffer warp can also be manipulated by a separate heddle.

The invention results in production of a velvet patterned carpet having interwoven binder warps, stuffer warp and front and back wefts, a first pile warp under a succession of first front wefts and all of whose first pile ends rise in the pile immediately between each first front weft and the adjoining front wefts on either side of the first front wefts, and a second pile warp under a succession of second front wefts, all of whose second pile ends rise in the pile immediately between each second front weft and the adjoining front wefts on either side of the second front wefts, the pile warp ends being entirely above the back weft and above the stuffer warp ends.

Describing the examples in illustration but not in limitation and referring to the drawings:

Figures 1, 2, 3, 3a, 4 and 4a, illustrate diagrammatically, with the warps extending in the plane of the paper, the preferred embodiment of the weave of the present

invention, each of Figures 1 to 4 illustrating a successive step or pick of the cycle.

In this weave the shed is illustrated at 100, made up of a pile warp 101 taken from a pile warp beam 102 over a whip roll 103 and manipulated by the eyes 104 of a pile warp heddle 105 in any suitable manner, preferably as later explained. A second pile warp 106 is taken from a second pile warp beam 107 over a whip roll 108 and is manipulated by the eyes 110 of a second pile warp heddle 111 operated in any suitable manner.

A stuffer warp 112 is withdrawn from a stuffer warp beam 113 over any suitable tensioning device 114 and, in the preferred embodiment of Figures 1 to 4, is guided by an elevated guide roll 115 (which may if desired be a whip roll). In this form the location of the guide roll 115 is important, as the stuffer warp ends between the guide roll 115 and the back heddle 104 must extend diagonally downward at an angle of at least 2° to prevent sag and inoperativeness of the weave. The guide roll 115 should accordingly be located above the level of the desired upper limit of the shed to be made by the stuffer warp ends. Thus in short, the stuffer warp ends must, in the form of Figures 1 to 4, be guided from a point above the top of the shed formed by the stuffer warp ends and sufficiently above to provide an angle of at least 2° of descent of the stuffer warp ends below the horizontal in Figures 2 and 4.

From the guide roll 115, the stuffer warp ends pass through the long slots 116 in pile warp heddles 105 and 111 below the eyes 104 and 110. The construction of 30 the pile warp heddles will be considered more in detail later. It is important to note at this point that, unlike most weaves, the stuffer warp ends are carried down by the concurrent action of two pile warp heddles rather than by a separate stuffer warp heddle in this form.

The long slot 116 should be longer than the height of the weave shed between the upper pile ends and the lay height of the shuttle way. The length must be sufficient to allow the stuffer warp to move to the bottom of the shed in one or more long slot heddles while a 40 heddle or heddles having other long slots are moved up to raise the pile to the top of the shed. Thus in a particular example where the distance between the upper pile ends and the lay height of the shuttle way was six inches, it was found desirable to make the long slot 45 116 for the stuffer warp ends seven and one-half inches long.

Binder warps 117 and 118 are withdrawn over suitable tension devices, not shown, from binder warp beam 120. The respective binder warps are manipulated by 50 binder warp heddles 121 and 122.

In Figure 1, pile warp heddle 105 is fully raised and binder warp heddle 111 is fully lowered, raising pile warp 101 and depressing pile warp 106 and stuffer warp 112 due to the long slot 116 in pile warp heddle 111. Binder 55 warp heddle 121 is raised half way, and binder warp heddle 122 is depressed, raising binder warp 117 and lowering binder warp 118. In this position of the shed, a wire 123 is inserted beneath pile warp 101 and above binder warp 117 in the mid position and also above binder warp 118, pile warp 106 and stuffer warp 112 in the lower position. A shot of weft is taken by shuttle 124 which passes under binder warp 117 and over binder warp 118, pile warp 106 and stuffer warp 112. This concludes the first step of the cycle as shown in Figure 1. 65

The next step in the cycle as shown in Figure 2 is accomplished by lowering pile warp heddle 105 to mid position, raising pile warp heddle 111 to mid position and retaining the positions of binder warp heddles 121 70 and 122 unchanged. As shown in Figure 2, both pile warps 101 and 106 are in mid position, and stuffer warp 112 is also in mid position as it pulls up to the tops of the long slots 116 due to the guiding from above by guide 115, and the tops of the long slots of the pile

warp heddles and particularly heddle 111 which is nearest to the shed are in the mid position. Binder warp 117 is also in mid position, while binder warp 118 is in lower position.

With this arrangement of the shed, a shot of weft is taken by shuttle 124 passing beneath both pile warps 101 and 106, stuffer warp 112 and binder warp 117 and above binder warp 118 as shown. The shot is then beaten up by reed 125.

In the third step of the cycle as shown in Figure 3, pile warp heddle 105 is in lower position, pile warp heddle 111 is in raised position, and the binder warp heddles are reversed, binder warp heddle 121 being in lower position and binder warp heddle 122 being raised half way. Thus in the shed, pile warp 106 is raised fully, binder warp 118 is raised half way and pile warp 101, stuffer warp 112 and binder warp 117 are fully depressed. With this arrangement of the shed, another wire 126 is inserted beneath pile warp 106, above binder warp 118 and of course above pile warp 101, stuffer warp 112 and binder warp 117. A shot of weft is taken by shuttle 124 beneath binder warp 118 and above pile warp 101, stuffer warp 112, and binder warp 117. The wire and shot are beaten up by reed 125. It will be evident that in Figure 3 the position of stuffer warp 112 is controlled by the lowering of pile warp heddle 105, the upper portion of whose long slot 116 depresses the stuffer warp. The stuffer warp as it is depressed moves down in the long slot of pile warp heddle 111 notwithstanding that the heddle is raised.

By reference to Figure 3a it will be seen that the weave is developing with pile warp 101 extending over wire 123 and then locked under one of the wefts 127². Likewise pile warp 106 is locked under weft 127 and is carried over wire 126. The chain warps 117 and 118 cross between wefts 127' and 127².

Stuffer warps 112 extend alternately under and over the wefts in the back of the fabric.

In the position shown in Figure 4, which constitutes the last step of the cycle, pile warp heddle 105 and pile warp 111 are both raised half way, raising pile warps 101 and 106 half way and positioning stuffer warp 112 in half raised position after the manner of Figure 2. The binder warp heddles and binder warps remain in the same position as in Figure 3. A shot of weft is taken by shuttle 124, which passes under pile warps 101 and 106, stuffer warp 112 and binder warp 118 and over binder warp 117. Figure 4a shows the additional step taken in the weave by inserting weft 127³. The cycle is completed by a beat of the reed 125.

It will be understood that the cycle outline in Figures 1 to 4 inclusive represents a velvet carpet weave which may be conventional except for the fact that two different pile warps are employed and separately manipulated, that the wires can be of unusual construction as later explained, and that the thread-in can also be unusual.

While in Figures 1 to 4 inclusive, I have shown the pile warps coming from separate beams 102 and 107, where the take-up in the fabric is the same in both warps and especially where the thread-in permits using ends in one warp which are not used in the other warp and vice versa, it will be understood that both warps can be taken from the same beam 128 as shown in Figure 5, which corresponds to Figure 1, the first step of the cycle, and thus indicates that a single beam can be used for two or more pile warps. To adjust to make the distance of each warp from the point of leaving the beam 128 to the point of utilization in the shed the same, the whip roll 103' for pile warp 101 in Figure 5 is made adjustable as shown in the arrows to permit convenient equalization of the lengths of the two warps.

The thread-in of the warps in the heddles of Figures 1 to 4 and 5 is shown diagrammatically in Figure 6 to make

the arrangement clearer. Thus it is shown that pile warp 101 passes through the eyes 104 of pile warp heddle 105 and stuffer warp 112 passes through the long slot 116 of this heddle which begins immediately below each eye. Binder warp 117 is threaded through binder warp heddle 121, binder warp 118 is threaded through binder warp heddle 122, pile warp 106 is threaded through the eyes 110 of pile warp heddle 111 and stuffer warp 112 is also threaded through the long slots 116 of pile warp heddle 111 immediately below the eyes.

In the weaving as illustrated in Figures 1 to 5 and particularly as shown in Figure 4a, it will be seen that the pile warps do not pass under the stuffer warp, so that a maximum amount of space in the back of the fabric is left for stuffer warps. This makes possible the production of a stiffer fabric by employing a plurality of stuffer warp ends at each dent of the heddle 105 and 111. Figure 7, which otherwise corresponds to Figure 6, shows three stuffer warp ends 112, 112' and 112² threaded-in through the long slots 116 of pile warp heddles 105 and 111.

It will be understood that several different processes can be followed to produce pattern effects in a velvet carpet as shown in Figures 1 to 4, inclusive, without using a jacquard or other selected pattern device. The individual pile warps 101 and 106 may differ in character for example because they are dyed a different color, or are of different construction, for example one of plain twist and one of hard twist or frieze, one of wool and

one of rayon or other artificial textile fiber, one of two-ply and one of three-ply, or one of crimped fiber and another of straighter fiber. Any of these or various other changes in the characters of the pile yarn will produce 5 a pattern effect by raising the different pile warps over wires on each cycle as shown. Whether or not differences in the character of the pile yarn of the two or more warps are employed, it is often desirable to vary the character of the wires, and this is illustrated in some detail particularly in Figures 8 to 12a inclusive. These various 10 figures show how it is possible without a selective pattern mechanism such as a jacquard to obtain an admixture of several different kinds of fabric in the same velvet carpet, such as cut and uncut, wavy and straight, and high and 15 low piles.

To simplify the discussion and avoid the excessive use of primes, various reference characters are being applied to designate wire characteristics on the two different types of wires 123 and 126 as shown in Figures 8 to 12a inclusive.

Table I shows in detail the characteristics present in various wire combinations which may be used. The figures are grouped in pairs, Figure 8 for example showing the wire construction of the wire set in perspective and Figure 8a showing the weave prior to withdrawal of the wires. The same relationship exists between Figure 9 and 9a and so on. Wires having straight upper surfaces throughout the portion of the wire over which the pile is formed are designated 130, while wires having

TABLE I

wavy upper surfaces are designated 131, wires having cutters are designated 132 (the cutters being shown merely conventionally, without attempting to illustrate the usual spoons and blades which are used), while wires having non-cutting ends are designated 133, high wires are marked 134, low wires are designated 135, wide wires are marked 136 and narrow wires are designated 137.

Table I illustrates the character of the wires in various combinations in respect to the straight or wavy character of the top of the wire at the portion where the pile is formed over the wire, the cutting or non-cutting character of the wire, the high or low character and the wide or narrow character, and rather than describe these features separately, this table should be consulted. Each of the weaves is comparable to that of Figure 4a except that it shows a particular example of the combination of straight and wavy wires, cutting and non-cutting wires, high and low wires and wide and narrow wires. No attempt has been made to indicate all of the various possibilities, but from the wide variety of illustrations it will be possible to observe that any one of the combination of wire characteristics can be employed with any one of the others. For the purpose of simplicity the wire sets illustrated in Table I involve two types of wires alternating, without disclosing combinations of three, four or more different wires arranged in successive series in the wire set.

It will be evident that combinations of three different wires may be used in which for example the first is a non-cutting wavy wire, the second is a low straight cutting wire and the third is a high straight non-cutting wire, all raising the same pile ends in succession.

It will be evident to those skilled in the art that further variations in the weaves thus described can be accomplished by providing at least one wire of the combination cutting, or at least one wire non-cutting, or at least one wire cutting and one wire non-cutting, or one wire higher than another, or one wire wider than another, or one wire wavy with or without one wire straight or one wire cutting or non-cutting. Thus one wire can be cutting, one wire non-cutting, one wire higher (which may be the cutting or the non-cutting wire) and one wire low; or one wire can be non-cutting, one cutting, one wide and one narrow; or one wire can be cutting, one non-cutting, one wavy and one straight; or one wire can be high, one low, one wavy and one straight; or one wire can be wide, one narrow, one wavy and one straight.

An additional feature which is subject to variation in any of the weaves of the invention or even in standard velvet carpet weaves, is the character of thread-in used in respect to presence of an end-out or blank dent in one or more of the pile warps, the number of piles per dent at a particular dent, the relation of the condition regarding ends-in or ends-out and number of ends-in in one pile warp at a particular dent and the similar or dissimilar condition at the corresponding dent of another pile warp, and the relation between ends-in and ends-out and the number of ends-in in a particular dent of one pile warp and the condition regarding concentration of pile in the dents on either side of that dent.

When reference is made herein to a dent it is intended to indicate a longitudinally extending row in the fabric which corresponds to a dent in the reed weaving that fabric. Thus at a particular dent there will normally be binder warp ends, one or more stuffer warp ends and anywhere from one to several pile warp ends depending on the thread-in.

It will be understood that by varying ends-out, ends-in and several ends-in in various dents, thread-in patterns can be produced which will affect the appearance of the fabric as will any other pattern, and produce new and desirable effects especially when combined with differences in character of pile and differences in wire construction already discussed.

Figures 13 to 15 suggest various conditions which can

prevail at a particular dent. In Figure 13 there are two pile ends 142 and 143 of pile warp 101 at the particular dent and two pile warp ends 144 and 145 of pile warp 106 at the same dent. This great pile concentration tends to cause an outward bulging of the pile at 146 on either side of the dent, which can be used to obtain superior coverage especially with low pile height if all dents are filled, or can be caused to distort the pile laterally into blank dents or dents which have ends-out as later explained.

Figure 14 illustrates the condition which obtains when a single pile warp end 142 of pile 101 is employed at a particular dent and ends-out or a blank dent is employed in pile 106. The pile tends to remain upstanding but better distribution is obtained by this combination of end 15 in at a particular dent of one pile and an end-out at the corresponding dent of the other pile or piles. Figure 15 illustrates the condition which prevails where a blank dent or end-out exists in both piles. Pile projections from dents on either side, as suggested by pile projections 147, 20 148, 150 and 151 from the dents at either side, crowds in at 152 toward the blank dent, thus creating a difference in the appearance of the top of the pile and giving rise to a pattern effect.

The condition that prevails with various combinations 25 of thread-in pattern is illustrated more clearly in Figure 16. The vertical columns in this figure indicate the conditions in eight numbered dents. The horizontal section at the top diagrammatically illustrates the number of ends-in in the particular dents of pile warps 101 and 106 and the horizontal divisions below indicate the conditions prevailing in warps 106 and 101 as indicated at various weft positions. In dent 1, pile warp 101 has one end-in and pile warp 106 has an end-out. As seen below, projections 153 from the end-in of pile warp 101 are 30 relatively upstanding and free from lateral deflection. At dent 2 the same thread-in is used and, if it were not for the condition in the next dent, pile projections 154 of pile warp 101 would remain uniformly upstanding. Dent 3, however, has a more crowded condition, since there is an end-in of pile warp 101 and an end-in of pile warp 106. Thus pile projections 155 of pile warp 101 tend to be crowded toward pile projections 154 and distort pile projections 154 toward dent 1 as suggested by the curve of pile projections 154. Pile projections 155 are themselves 35 distorted toward dent 2 as suggested by their curving. Due to the crowded condition also, pile projections 156 of pile warps 106 are distorted toward dent 4 as indicated by their curving. In dent 4 the thread-in is an end-out of pile warp 101 and an end-in of pile warp 106. Pile 40 projections 157 of pile warp 106 would therefore remain upstanding except for the crowded condition in dent 3, which tends to force pile projections 157 toward dent 5. Dent 5 uses the same thread-in as dent 4, and pile projections 158 would therefore be uniformly upstanding were it not for the crowded condition in dent 6, which has the same thread-in as dent 3. Pile projections 160 of pile warp 101 are therefore forced toward dent 5 and tend to distort pile projections 158 toward dent 4 as shown. Pile 45 projections 161 of dent 6 on the other hand are distorted toward dent 7, and this is particularly so as dent 7 employs ends-out in both pile warps. Dent 8 has the same thread-in as dent 3 and due to the crowded condition pile projections 162 of pile warp 101 are forced toward blank dent 7. Assuming that the next dent, not shown, has a crowded condition, pile projections 163 of pile warp 106 are also forced toward blank dent 7 as shown.

By examining the over-all appearance of Figure 16, it will be noted that a serpentine pattern or worm is created in dents 2, 3 and 4 and a further serpentine pattern is created in dents 6, 7 and 8, the serpentine pattern in dents 2, 3 and 4 being comparatively narrow while the serpentine pattern in dents 6 and 8 is wider due to the effect of the ends-out in both warps of dent 7 in spreading the adjoining pile projections.

Figure 17 illustrates the condition in a number of

practical thread-in patterns numbered at the right from one to 10 inclusive. The diagram shows in vertical columns 10 dents for each pattern, it being understood that where blanks are used at the right of the diagram, the same thread-in pattern is repeated continuously across the diagram. The upper portion of each thread-in pattern diagram shows the condition in warp 101 and the lower portion shows the condition in warp 106 at the particular dents illustrated. For example, the presence of a dot at a particular dent position indicates that there is an end-in at that position and the presence of a blank indicates that there is an end-out at that position. Where there are two dots at a particular dent and warp position, it means that there are two ends-in and where there are three dots it means that there are three ends-in.

Beginning at the left of thread-in pattern 1, there is an end-in in pile warp 101 and an end-out in pile warp 106, then an end-in in pile warp 101 and an end-out in pile warp 106, then an end-in in pile warp 101 and an end-out in pile warp 106. The pattern then reverses and the next dent has an end-out in pile warp 101 and an end-in in pile warp 106 followed by an end-out in pile warp 101 followed by an end-in in pile warp 106, followed by an end-out in pile warp 101 and an end-in in pile warp 106, continuing thus across the portion of the fabric using this thread-in pattern. Without repeating the diagram it will be noted that I can employ two ends-in in this pattern everywhere I show an end-in, or three or four ends-in everywhere I show an end-in, without changing the ends-out.

Thread-in pattern 2 begins at the left with an end-in in pile warp 101 and an end-out in pile warp 106, followed in the next dent by an end-in in pile warp 101 and an end-out in pile warp 106, followed in the next dent by an end-out in pile warp 101 and an end-in in pile warp 106, followed in the next dent by an end-out in pile warp 101 and an end-in in pile warp 106, continuing across the fabric as desired.

Thread-in pattern 3 begins at the left with an end-in in pile warp 101 and an end-out in pile warp 106, followed in the next dent with an end-out in pile warp 101 and an end-in in pile warp 106, and so on across the portion of the fabric using this thread-in pattern. Instead of the pattern shown in the first dent I can use two or three ends-in in each warp in the first dent.

It will be understood that in each of the above cases, there is a combination of an end-in or ends-in in a particular dent of one pile warp and an end-out of the corresponding dent of the next pile warp, which aids in giving better pile distribution. In some cases there are a series of ends-in in one pile warp corresponding to ends-out in the other pile warp, and then a reversal according to the pattern design.

In some cases it is desirable to produce a concentration of pile and thread-in pattern 4 employs an end-in in pile warp 101 and an end-in in pile warp 106 in each dent, there being no blank dents in this case.

Thread-in pattern 5 starts in the left hand dent with ends-in in both pile warps and in the next dent employs an end-in in pile warp 101 and an end-out in pile warp 106, followed in the next dent by ends-in from both pile warps, followed in the next dent by an end-out in pile warp 101 and an end-in in pile warp 106.

Thread-in pattern 6 is similar, but utilizes a repetition of the condition in the second dent for the third dent and a repetition of the condition in the fifth dent for the sixth dent.

Thread-in pattern 7 is an elaboration of thread-in pattern 5. In the first and second dent there is an end-in from each pile warp, in the third, fourth and fifth dents there is an end-out from pile warp 101 and an end-in from pile warp 106. The sixth and seventh dents are repetitions of the first and second dents and the eighth, ninth and tenth dents each have an end-in from pile warp 101 and an end-out from pile warp 106.

Thread-in pattern 8 is similar to thread-in pattern 5 75

in the first dent, has a second dent like the first dent of thread-in pattern 5, then follows with two dents like the second dent of thread-in pattern 5 and finally has two dents like the fourth dent of thread-in pattern 5.

In some cases it is desirable to employ a plurality of ends per dent in both pile warps to obtain very good coverage with a very short pile. Thread-in pattern 9 shows two ends from each pile warp per dent and thread-in pattern 10 shows three ends from each pile warp per dent. In this case, the pattern effect will usually be produced by the difference in wire construction or the difference in character of pile.

The feature of using a plurality of ends per dent may be employed in one warp with fewer ends per dent at corresponding dents in the other warp, or with ends-out at corresponding dents in the other warp.

A particularly desirable coverage is obtained from thread-in pattern 3, and this can be modified by employing a series of ends-in in one warp corresponding with ends-out in the other warp as in thread-in patterns 1 and 2.

While it will usually be desirable to employ the thread-in patterns with combinations of different wires and combinations of different pile warps, it will be understood that the thread-in patterns can also be used to advantage even without difference in pile character and pile projection dimension, and some advantage can be obtained from this feature even when only a single pile warp is employed.

To illustrate more clearly the different aspects obtained from different thread-in patterns used with different wires, Figures 18, 19 and 20 illustrate selected portions of a blanket woven with different thread-in patterns and different wire combinations. Reading from right to left on these figures, each vertical column as indicated on the figures corresponds to one of the thread-in patterns 1 to 8 shown diagrammatically in Figure 17. The repeat of wires in the wire sets employed in the different views are as follows:

Wire set A (upper portion of Figure 18):

Straight non-cutting wire of height 0.290"

Wavy non-cutting wire varying in height from 0.142" to 0.213"

Straight cutting wire of height 0.110"

Wire set B (lower portion of Figure 18):

Straight non-cutting wire of height 0.290"

Straight cutting wire of height 0.110"

Straight cutting wire of height 0.110"

Wire set C (upper portion of Figure 19):

Straight cutting wire of height 0.200"

Straight cutting wire of height 0.110"

Straight cutting wire of height 0.110"

Wire set D (lower portion of Figure 19):

Straight cutting wire of height 0.260"

Straight cutting wire of height 0.110"

Straight cutting wire of height 0.110"

Wire set E (upper portion of Figure 20):

Straight non-cutting wire of height 0.290"

Wavy non-cutting wire varying in height from 0.142" to 0.213"

Straight cutting wire of height 0.110"

Wire set F (lower portion of Figure 20):

Straight cutting wire of height 0.200"

Straight non-cutting wire of height of 0.160"

Straight non-cutting wire of height of 0.160"

It will be evident from studying Figures 18, 19 and 20 that they illustrate 48 different fabrics comprising 8 different thread-in patterns woven with six different wire sets, the upper portion of each figure corresponding to one wire set and the lower portion to another wire set. The distinctly different highlights and shades illustrate the results achieved by the combination of different wire sets and different thread-in patterns weaving light and

dark pile warps. It will be understood of course that the particular effects achieved are intended to be illustrative of the various possibilities.

By the process of the invention as illustrated in Figures 18, 19 and 20 it will be seen that the fabrics show textured effects obtained from a plurality of fabric face levels which are highly fashionable and in demand, and are now only produced on the relatively expensive Wilton looms with jacquard mechanism. The Wilton loom is expensive in first cost, in maintenance and because of low production as compared with the low cost modified velvet or tapestry loom of the invention.

In the weaves just discussed, unlike some of the weaves previously illustrated, each different pile warp is subject to each different type of wire, instead of employing the same type of wire continuously for the same pile warp.

If the number of pile warps is an even number, such as 2, 4, 6 or 8, the number of pile wires in the wire repeat must in this case be odd, such as 3, 5, 7 or 9, so that the same type of wire will operate on the different warps. Sometimes, however, as earlier explained, it is preferable to have one type of wire operate always on one warp, and another type of wire operate on another warp.

For best results, the slope on the wavy wire should be 10 to 15° in both directions from the high to the low points.

As already described, the weaves of the present invention produce a uniform smooth clean back, on which pile warps are not visible. Figure 21 illustrates the back 164 of the blanket shown in Figures 18, 19 and 20. It will be noted that this back is not marred by pile yarn or other irregularities.

The effect of different thread-in patterns is shown in Figures 22 to 24, which illustrate the condition of the weave at a particular dent for thread-in conditions indicated in the diagram at the left of each figure. In Figure 22 the thread-in pattern at the particular dent calls for an end-in in pile warp 106 and an end-out in pile warp 101. Accordingly pile projections 138 from the end of pile warp 106 are present but the end from pile warp 101 is completely lacking at that dent.

In Figure 23 the thread-in pattern calls for an end-in from both pile warps at the particular dent and accordingly at that dent pile projections 138 and 140 from the respective pile warps are present.

Figure 24 illustrates the condition at a dent where the thread-in diagram calls for two ends from each of the warps 101 and 106. Accordingly, there are two warp ends 106 and 106' present, producing pile projections 138 and two warp ends 101 and 101' producing pile projections 140. For convenience in illustration, the diagram shows these warp ends lying one below another, whereas of course they can be one beside another.

Thus it will be understood that with an end-in in one dent of one pile warp cooperating with an end-out of the corresponding dent of the other pile warp (or warps if there are more than two warps), the alignment of the pile is distorted into a staggered or interlocking relationship in both the longitudinal and transverse directions so that the fabric does not open up in the conventional manner when the back is bent along a longitudinal or transverse line to bring two parts of the back together. When viewed on the floor, the usual stripes in both directions are not visible. The orientation of the pile projections is diagonal rather than transverse or longitudinal.

Figure 24a illustrates in top plan a conventional weave made with pile projections of a single warp in two transverse rows 139' and 139² and with two ends per dent. The pile projections are separated by a clear line 139³ transversely and 139⁴ longitudinally. Figure 24b shows a weave of the invention, woven with thread-in pattern 4 of Figure 17, that is, one end of each pile per dent. Here there is a staggered relationship 139⁵ of pile ends transversely, and a staggered relation 139⁶ longitudinally.

If a thicker yarn is used, and thread-in pattern 3 of Figure 17 is employed (that is, an end-in in one pile and an end-out in the corresponding dent of the other pile, then in the next dent an end-out in the one pile and an end-in in the other pile, and so on), a staggered transverse line 139⁷ and staggered longitudinal line 139⁸ is produced in Figure 24c, with a straight diagonal line 139⁹. One of the great advantages in pattern 3 is that it permits the use of thicker pile yarn than has normally been employed and gives better coverage. The prior art of Figure 24d, has straight transverse lines 139¹ and longitudinal lines 139².

Figure 25 shows in perspective the velvet loom desirably employed in the weave of the invention and indicates that the loom may, in most respects, be conventional. This view illustrates the shed 100 and the reed 125 and the heddles 111, 122, 121 and 105 described in Figures 1 to 4 inclusive. The heddles are manipulated by heddle harness 165 of any conventional character from cams to be described. The shuttle moves in a guideway 166 under the action of picking sticks 167, of which one only is shown. The fabric 168 which has been woven is carried over its take-up roll, not shown.

Figure 26 illustrates a wire motion 170 of any suitable conventional character which is shown inserting a wire 123 of any of the characters above referred to in the shed. This view illustrates that the wire motion can be conventional, the only change being in the wire construction itself.

Figure 27 illustrates another phase of the wire motion 170 which may be conventional, and shows the withdrawing of wire 123 from the end of the wire set 171. It will be evident that any suitable velvet loom may be used with minor modification in the heddles and in the feed of the stuffer warp (if the weave of Figures 1 to 4 is employed).

The lateral relationship between the high points of the wavy wires, when wavy wires are employed, may introduce a pattern effect.

The modification in the pile warp heddles is conveniently accomplished by changing the heddle wires to use new heddle wires 174 shown in detail in Figure 28 and suitable for application in heddles 105 and 111. Each of these heddle wires has an eye 104 (or 110) and a long slot 116 immediately below the eye, with vertically extending stems 175 and 176 for attachment in the heddle.

The heddle motion can conveniently be modified as shown in Figure 29, which illustrates diagrammatically the motion for one heddle 105. The harness 165 supporting the heddle 105 consists of a bell crank 177 pivoted on a fixed pivot 178 and at one end supporting a heddle suspension 180. The other end is pivotally connected by adjustable link 181 to a lever 182 having fixed pivot at 183 on the frame 184. The lever at the opposite end from link 181 pivotally connects to link 185 which makes pivotal connection with rocker 186 having fixed pivot 187 on the frame. Link 185 has an extension 188 which makes pivotal support with a bottom connection 190 to the heddle. Rocker 182 carries a cam follower arm 191 on which a follower roller 192 is pivotally mounted. The follower roller engages in a cam track 193 of a face cam 196 turning on cam shaft 195 of the loom.

Figure 30 illustrates cam 196 for heddle 105, cam 194 for heddle 121, cam 197 for heddle 122 and cam 198 for heddle 111, and shows around each cam numbers 1, 2, 3 and 4 corresponding to the pick positions of Figures 1, 2, 3 and 4 respectively. It will, of course, be evident that the detail of the cam construction will vary with the individual harness which operates the individual heddles, and the showing in Figure 30 is accordingly merely illustrative of one suitable cam construction.

While Figures 1 to 4 are arranged for a weave in which the pile warp heddles manipulate the stuffer warp, it will be evident that the same weave can somewhat less desirably be obtained by using a separate heddle to manipu-

late the stuffer warp. In this case the elevated guide roll is not necessary.

It will be evident that the invention will result in producing a patterned velvet pile carpet having stuffer and binder warps on a velvet loom without a selective pattern control mechanism and without printing, and that the fabric thus produced can possess very unusual appearance characteristics which combine the effects of several different fabrics, while at the same time the face yarn consumption is very economical and the backing is clean and uniform.

Where reference is made to a warp herein, it is understood that it designates a group of yarns which run lengthwise, manipulated by a shed device such as a heddle. One of the warp yarns is termed an "end."

Where a cycle is referred to in operation of the loom, it is intended to designate a sequence of operations until a repeat is encountered.

Where reference is made to weaving on the velvet carpet system, it is intended to include the tapestry system and to designate weaving a warp pile fabric where all ends of a particular pile warp are raised by heddles without pattern selection of the ends to be raised, and transverse wires are inserted.

In view of my invention and disclosure variations and modifications to meet individual whim or particular need will doubtless become evident to others skilled in the art, to obtain all or part of the benefits of my invention without copying the process, structure and fabric shown, and I, therefore, claim all such insofar as they fall within the reasonable spirit and scope of my claims.

Having thus described my invention what I claim as new and desire to secure by Letters Patent is:

1. The process of weaving a pile carpet, using a plurality of pile warps and for each of the pile warps a heddle having an eye and a long slot below the eye at each dent position, the long slot having a height greater than the shed height, which comprises threading each pile warp through eyes of a different one of the heddles, extending a stuffer warp downwardly and then threading each of the stuffer warp ends through a long slot of both pile warp heddles, fully raising one heddle and thus raising one pile warp, fully lowering the other heddle nearer to the shed and thus lowering another pile warp and lowering the stuffer warp by the conjoint action of the two heddles, raising one chain warp half way and lowering the other chain warp, inserting a wire beneath the raised pile warp, and above both chain warps, the lowered pile warp and the stuffer warp, inserting a shot of weft beneath the raised pile warp and beneath the raised chain warp and above the lowered chain warp, the lowered pile warp and the stuffer warp, beating up, lowering the one heddle half way and thus lowering the one pile warp half way, raising the other heddle nearer to the shed half way and thus raising the other pile warp half way and raising the stuffer warp half way by the conjoint action of the two heddles, maintaining the chain warps unchanged, inserting a shot of weft beneath the pile warps, the one chain warp and the stuffer warp and above the other chain warp, beating up, lowering the one heddle and thus lowering the one pile warp, fully raising the other heddle nearer to the shed and thus raising the other pile warp by the conjoint action of the two heddles, reversing the chain warps, inserting a wire beneath the other pile warp and above both chain warps, the one pile warp, and the stuffer warp, inserting a shot of weft beneath the other pile warp and the other chain warp and above the one chain warp, the one pile warp and the stuffer warp, beating up, raising the one heddle half way and thus raising the one pile warp half way, raising the other heddle nearer to the shed half way and thus raising the other pile warp half way and raising the stuffer warp half way by conjoint action of the two heddles, maintaining the positions of the chain warps, inserting a shot of weft under the other chain

warp, under both pile warps, and under the stuffer warp and above the one chain warp, and beating up.

2. A velvet carpet loom having a shed position, means for supplying pile warps, means for supplying binder warp ends and a stuffer warp beam, a guide for the stuffer warp behind the shed elevated above the top of the shed position, for supplying stuffer warp in a generally downward direction, binder warp heddle-means receiving binder warp ends, a plurality of pile warp heddles each having a guiding opening which receives the ends of one of the pile warps and each having a long slot longer than the height of the shed which receives the ends of the stuffer warp, the stuffer warp passing through the long slots of both of the heddles which manipulate the pile warps, means for introducing wires and means for inserting shots of weft in the shed.

3. The process of weaving according to claim 1, which comprises feeding the stuffer warp to the shed from the back at a level just above the midposition.

4. The process of weaving a pile carpet, using at least two pile warps and for each pile warp using a heddle having an eye and a long slot below the eye, the long slots having a height greater than the shed height, and using suitable binder warp ends, which comprises threading each pile warp through eyes of a different one of the heddles, extending a stuffer warp downwardly and then threading each of the stuffer warp ends through a long slot of both pile warp heddles, fully raising one heddle and thus raising one pile warp, fully lowering the other heddle nearer to the shed and thus lowering another pile warp and lowering the stuffer warp by the conjoint action of the two heddles, forming an upper shed and a lower shed, inserting a wire in the upper shed, inserting a shot of weft in the lower shed, lowering the one heddle half way and thus lowering the one pile warp half way, raising the other heddle nearer to the shed half way and thus raising the other pile warp half way and raising the stuffer warp half way by the conjoint action of the two heddles, forming a lower shed, inserting a shot of weft in the lower shed, lowering the one heddle and thus lowering the one pile warp, fully raising the other heddle nearer to the shed and thus raising the other pile warp and lowering the stuffer warp by the conjoint action of the two heddles, forming an upper shed and a lower shed, inserting a wire in the upper shed, inserting a shot of weft in the lower shed, raising the one heddle half way, raising the other heddle nearer to the shed half way and thus raising the other pile warp half way and raising the stuffer warp half way by the conjoint action of the two heddles, forming a lower shed, and inserting a shot of weft in the lower shed.

5. The method of weaving a pile carpet, which comprises interweaving pile warp ends, binder warp ends, stuffer warp ends and wefts, and in the weaving manipulating the warp ends of one of the warps by the conjoint action of two heddles.

6. The method according to claim 5, in which the stuffer warp is manipulated by the conjoint action of two heddles.

7. The process of weaving pile carpet, using a loom having a reed, which comprises threading-in pile warp A through the reed, threading-in pile warp B through the reed and, in threading-in the said warps, inserting in one dent a first total number of pile warp ends and in another dent a different total number of pile warp ends, which different total number can be as small as zero, interweaving binder warp ends, stuffer warp ends and wefts with pile warp A and pile warp B, and on each cycle successively raising pile warp A and pile warp B over wires, thus creating pattern effects through lateral crowding of the pile projections due to the variation in the number of pile warp ends per dent.

8. The process according to claim 7, which comprises threading-in a plurality of pile warp ends per dent in at

least some dents and a different number of pile warp ends per dent in other dents.

9. The process according to claim 7, which comprises threading-in a plurality of pile warp ends per dent in at least some dents and leaving ends-out of at least one of the pile warps in certain dents. 5

10. The process according to claim 7, which comprises threading-in both pile warp A and pile warp B with ends-out at the same dents in certain dents.

11. The process according to claim 7, which comprises 10 threading-in both pile warp A and pile warp B with a plurality of ends-in in corresponding dents at certain dents and with ends-out at corresponding dents at certain other dents.

12. The process according to claim 7, which comprises 15 threading-in a plurality of ends of pile warp A and of pile warp B in the same dents at certain dents.

13. The process according to claim 7, which comprises threading-in an end of pile warp A and an end of pile warp B in the same dent, threading-in an end of only one 20 of the pile warps in the next dent, threading-in an end of pile warp A and an end of pile warp B in the next dent, and threading-in an end of only one of the pile warps in the next dent.

14. The process according to claim 7, which comprises 25 threading-in an end of pile warp A and an end of pile warp B in one dent, threading-in an end of only one pile warp in the next dent, threading-in an end of only one pile warp in the next dent, threading-in an end of pile warp A and an end of pile warp B in the next dent, 30 threading-in an end of only one pile warp in the next dent, and threading-in an end of only one pile warp in the next dent.

15. The process according to claim 7 which comprises threading-in an end of pile warp A and an end of pile 35 warp B in each of a first plurality of adjoining dents, threading-in an end of only one pile warp in each of a second plurality of adjoining dents next to the first, threading-in an end of pile warp A and an end of pile warp B in each of a third plurality of adjoining dents next to the 40

second, and threading-in an end of pile warp A and an end of pile warp B in each of a fourth plurality of adjoining dents next to the third.

16. The process according to claim 7, which comprises threading-in an end of pile warp A and an end of pile warp B in each of a series of adjoining dents, next thereto threading-in an end of pile warp A only in each of a series of adjoining dents and next thereto threading-in an end of pile warp B only in each of a series of adjoining dents.
